(57) **CLAIM**

The ornamental design for a tire, as shown and described.

DESCRIPTION

FIG. 1 is a front view of a tire according to the present application;

FIG. 2 is a rear view of the tire according to the present application;

FIG. 3 is a left view of the tire according to the present application;

FIG. 4 is a right view of the tire according to the present application;

FIG. 5 is a top view of the tire according to the present application;

FIG. 6 is a bottom view of the tire according to the present application; and,

FIG. 7 is a perspective view of the tire according to the present application.

The dash/dash/dash broken lines in the drawings depict environment and form no part of the claim.

The dash/dot/dot/dash broken lines in the drawings define the bounds of the claimed design and form no part thereof.
